UNITED STATES PATENT OFFICE.

GEORGE M. HOLLEY, OF BRADFORD, PENNSYLVANIA.

DESIGN FOR A CRANK-HANGER FOR MOTOR-CYCLES.

SPECIFICATION forming part of Design No. 33,599, dated November 20, 1900.

Application filed October 26, 1900. Serial No. 34,513. Term of patent 14 years.

To all whom it may concern:

Be it known that I, GEORGE M. HOLLEY, a citizen of the United States, residing at Bradford, in the county of McKean and State of Pennsylvania, have invented and produced a new and original Design for Crank-Hangers for Motor-Cycles, of which the following is a specification, reference being had to the accompanying drawing, forming a part thereof.

10 This design relates to the configuration of a crank-hanger for motor-cycles.

15 The accompanying drawing is a perspective view of a crank-hanger for motor-cycles embodying my design.

15 As shown in the accompanying drawing, the leading feature of my design consists of a large cylindrical case A, a smaller cylindrical case B, arranged in front of the large case and connected therewith by a short neck 20 b, a comparatively large nipple C, projecting

upwardly from the upper side of the large case, two small nipples d d, projecting upwardly from the large case on opposite sides of the large nipple, and two small nipples e e, projecting laterally from the sides of the large 25 case adjacent to the small upper nipples d d. The large upper nipple is provided with a marginal flange c, and the large case is provided on its outer side at intervals with ribs a, arranged parallel to the axis of this case. 30

What I claim is—

The design for a crank-hanger for motor-cycles, substantially as herein shown and described.

Witness my hand this 9th day of October, 35 1900.

GEORGE M. HOLLEY.
